UNITED STATES PATENT OFFICE.

RUSSELL S. WOLFE, OF ORANGEBURG, SOUTH CAROLINA.

FENCE-WIRE TWISTER.

Application filed August 27, 1923. Serial No. 659,663.

To all whom it may concern:

Be it known that I, RUSSELL S. WOLFE, a citizen of the United States, residing at Orangeburg, in the county of Orangeburg and State of South Carolina, have invented new and useful Improvements in Fence-Wire Twisters, of which the following is a specification.

The principal object of this invention is to provide means for splicing woven wire fence sections so that the meshes will be of the same size throughout.

Another object of the invention is to provide means whereby the two ends of a pair of horizontal wires can be wrapped around each other at one operation.

This invention also consists in certain other features of construction and in the combination and arrangement of the several parts, to be hereinafter fully described, illustrated in the accompanying drawings and specifically pointed out in the appended claims.

In describing my invention in detail, reference will be had to the accompanying drawings wherein like characters denote like or corresponding parts throughout the several views, and in which:

Figure 1 is a plan view of the device.

Figure 2 is a side view thereof.

Figure 3 is a longitudinal sectional view.

Figure 4 is a section on line 4—4 of Figure 1.

Figure 5 is a section on line 5—5 of Figure 1.

Figure 6 is a view of two wires twisted together.

In these views 1 indicates a block which is provided with a longitudinally extending bore 2 and a slot 3 which extends through the top and is in communication with the bore. The block is also provided with a threaded hole 4 in its center which has its bottom arranged slightly above the bottom 45 of the bore, the bottom of the hole being provided with a semi-circular recess 5. The sides of the block are provided with slots 6 which communicate with the hole 4. An operating member 7 is located at each end of the device and is rotatably mounted in the ends of the bore. Each member consists of a rectangular head part 8 and a tubular part 9. Each member is rotatably mounted in the bore by means of the collar 10 and the bushing 11. Each member is provided with a slot 12 which communicates with the cir-

cular opening of the member. The collar 10 engages the shoulder 13 which is formed by the raised bottom of the hole 4. A screw threaded plug 14 engages the hole 4 and acts as a clamp for holding the fence sections in the device. Each of the operating members carries a split ring 15 which acts as a lock for holding the bent up end of the wire in the curved slot 16 of the member, each ring being provided with a similar slot 16'. The head parts 8 are provided with holes 17 for receiving a spike or the like for facilitating the turning of the member or said members can be turned by a wrench applied to the head part. The plug 14 is also provided with a hole 18 for the same purpose and with a flattened part for receiving the wrench.

As shown in Figure 1 the device is placed on a pair of fence sections A and B with a pair of horizontal wires passing through the bore 2 and with a pair of the vertical wires passing through the slots 6. This will bring the twisted parts C in the hole 4. The plug is then screwed home so as to hold the wires in the device and attention is called to the fact that by making the hole of less depth than the bore the horizontal wires will be held off the bottoms of the operating members and thus reduce friction when the members are turned. The ends of the horizontal wires are bent at right angles, as shown at D and pass through the curved slot 16 in the operating members and then the rings 15 are turned to lock them in the slots by having their slots 16' engage the bent ends of the wires. The operating members are then rotated and thus the bent ends will be twisted around the wires to firmly fasten the sections A and B together. After a pair of horizontal wires have been fastened together in this manner the device is removed from these wires and placed in engagement with the next pair of wires and so on until all the horizontal wires have been twisted together. By placing the vertical wires in the slots 6 the meshes will be kept at the same dimensions at the splice as in the rest of the fence, thus providing a neat appearance and making it easier to stretch the fence.

While the device is mainly intended for splicing wire it will of course be understood that it may be made large enough to twist rods together though in this case the operating members would have to be rotated

by power means when handling large rods. The rods when very large could be heated.

It is thought from the foregoing description that the advantages and novel features 5 of my invention will be readily apparent.

I desire it to be understood that I may make changes in the construction and in the combination and arrangement of the several parts, provided that such changes fall within 10 the scope of the appended claims.

What I claim is:—

1. A wire splicer for splicing woven wire fence sections comprising a grooved support, 15 means for holding the wires therein, a pair of rotary members in the support having grooves therein for receiving the horizontal wires, means for connecting the ends of the wires to the members so that said ends will be twisted around the wires when the 20 members are rotated and the support having slots therein for receiving the vertical wires.

2. A wire splicer comprising a support having cross grooves therein for receiving the horizontal and vertical wires of the fence 25 sections to be connected together, centrally arranged means for holding the wires in the grooves, a pair of grooved members rotatably mounted in the support and means for

connecting the ends of the horizontal wires to said members. 30

3. A wire splicer comprising a support having cross grooves therein for receiving the horizontal and vertical wires of the fence sections to be connected together, centrally arranged means for holding the wires in the 35 grooves, a pair of grooved members rotatably mounted in the support, means for connecting the ends of the horizontal wires to said members, such means consisting of notches in the members and locking rings 40 for holding the wire ends in said notches.

4. A wire splicer comprising a block having cross grooves therein for receiving the horizontal and vertical wires of the fence sections that are to be connected together, 45 said block having a hole therein at the junction of the grooves, a threaded plug engaging the hole to hold the wires in position, a pair of operating members rotatably mounted in the block and having grooves 50 therein for receiving the horizontal wires and means for connecting the ends of the horizontal wires to said members.

In testimony whereof I affix my signature.

RUSSELL S. WOLFE.
